UNITED STATES PATENT OFFICE.

ANDREW ALTMAN, OF ELIZABETH, NEW JERSEY.

CAN-OPENER.

SPECIFICATION forming part of Letters Patent No. 613,653, dated November 8, 1898.

Application filed August 2, 1897. Serial No. 646,787. (No model.)

To all whom it may concern:

Be it known that I, ANDREW ALTMAN, a citizen of the United States, residing at Elizabeth, in the county of Union and State of New Jersey, have invented certain new and useful Improvements in Can-Openers; and I do hereby declare the following to be a full, clear, and exact description of the invention, such as will enable others skilled in the art to which it appertains to make and use the same, reference being had to the accompanying drawings, forming a part of this specification.

This invention relates to new and useful improvements in can-opening tools, and has for its object to provide a cheap, durable, and useful device that may be employed for the purpose of easily and quickly removing or opening the tops of cans.

The invention consists in the general construction and arrangement of the various parts to be hereinafter described, and particularly pointed out in the claim.

Referring to the accompanying drawings, Figure 1 is a side elevation illustrating a can-opener and corkscrew in position for use. Fig. 2 is a longitudinal section showing the receptacle in which the tools not in use are carried. Fig. 3 is a partial section illustrating the manner of securing the tools to the holder.

Like letters of reference refer to corresponding parts throughout the various figures.

A indicates the universal handle, within one end of which is formed a tool-receptacle *a*, arranged to carry within it the implements to be employed therewith. This receptacle is inclosed by means of the swinging door *B*, which is pivoted at its inner end upon a screw *a'* and is arranged when in position over the receptacle to swing below the edges thereof, thus forming a secure means by which the door is held from disengagement. At *a'* a notch is provided in the end wall of the receptacle to permit a small instrument to be inserted in under the edge of the cover, whereby it is raised out of the recess to be swung sidewise upon its pivot, by which access may be had to the receptacle.

Suitably located at the opposite end of the holder are a number of pockets *b*, *c*, and *d*, adapted to receive and engage the tools, wherein they are held in position for use.

The pockets *b* and *c* extend through the holder from side to side and at right angles to the long axis thereof, while the pocket *d* is formed in the extreme outer end, opposite the tool-receptacle and at right angles to the pockets *b* and *c*. The shanks of the tools and pockets within which they are engaged are preferably made somewhat tapering and rectangular in cross-section, so that when they are united the tool will be brought to a firm rigid seat and held from all lateral motion.

Upon one side of the holder, at that end in which the pockets are formed, there is a double spring-catch *C*, secured at its middle point by means of the screw *e* and provided at its free end with locking-pins *f* *g* to engage through the holes *h* and *j*, which are arranged to enter the tool-pockets *b* and *d* at their edges, and as the shanks of the tools are provided with notches at *l* to register with these holes the pins *f* *g* are forced into engagement therewith, thus securely locking the tools in position.

In Fig. 1 the holder is shown as fitted with a can-opening tool, consisting of a cutting-knife *m* and a tool *n*, which is provided with a pointed end to penetrate the can, and a right-angled portion at *m'* to form a pivot upon which the holder is turned in the process of opening said can. This cutting-knife is held in the pocket *c*, which intersects the pocket *d*, by providing in its shank a hole or recess *p*, and upon the inner end of the tool *n* a lug *p'*, so that when the tools are inserted in their respective pockets the lug and hole engage, and as the pin *g* upon the outer end of the spring *C* drops into the notch *l* in the shank of the tool *n* the parts are securely locked together.

It will be obvious that some slight modifications may be made in the general construction and arrangement of my improved tool without materially affecting the results, and I desire to have it understood that while I have preferred to illustrate my invention in connection with the particular class of implements herein shown and described I do not desire to limit myself thereto.

Having thus described my invention, what I claim is—

As a new article of manufacture, a can-opener, comprising a handle, in one end of

which pockets are formed, one of said pockets lying in axial line with said handle, the other of said pockets intersecting at right angles the first-named pocket, can-opening tools, comprising a centering pivot-point and an opening-blade held within said pockets, the opening-blade adapted to secure the centering-point in place in the handle, and a spring-

compressed pin adapted to hold the blade in place, substantially as described. 10

In testimony whereof I affix my signature in presence of two witnesses.

ANDREW ALTMAN.
